UNITED STATES PATENT OFFICE

FRANK HERST, OF WILMINGTON, NORTH CAROLINA

BOAT-PROPELLER UNIT

Application filed January 31, 1929. Serial No. 336,473.

This invention relates to the class of marine propulsion and pertains particularly to an improved propeller unit.

The primary object of this invention is to provide a propeller unit designed to be attached to the stern post of a boat, which will permit of the placing of the engine directly in the rear of the boat instead of midway between the bow and stern as in the usual practice.

Another object of the invention is to provide a unit which will make possible the simplification of the building of the boat for the reason that no shaft log will be required and consequently the difficulties encountered in making the boat water-tight thereabout will be eliminated.

The present invention broadly contemplates the provision of an elongated casing having a head and sleeve-like base portion, the casing being designed to be secured directly against the stern post of the boat. In the upper portion of the casing two bearings are formed, one thereof being in the nature of a sleeve which extends through the stern post into the boat. These bearings support the rear end of the motor drive shaft.

The drive shaft within the head of the casing carries a bevelled gear which meshes with a similar gear mounted upon a vertical shaft which extends into the lower or sleeve portion of the casing carrying upon its lower end a bevelled gear which in turn meshes with a pivoted gear carried by a short propeller shaft, which is rotatably mounted in the sleeve and extends through one side to the exterior of the casing where it carries a propeller.

With the propeller unit embodying this invention, the installation of the engine motor is made easier. The motor may be mounted to sit horizontally, thereby eliminating oiling difficulties.

The invention will be best understood from a consideration of the following detailed description taken in connection with the accompanying drawing forming a part of this specification, with the understanding, however, that the invention is not confined to any strict conformity with the showing of the

drawing but may be changed or modified so long as such changes or modifications mark no material departure from the salient features of the invention as expressed in the appended claims.

In the drawing:

Figure 1 is a diagrammatic view showing the unit embodying this invention applied to a boat;

Figure 2 is a longitudinal sectional view of the unit;

Figure 3 is a sectional view taken upon the line 3-3 of Figure 1;

Figure 4 is a sectional view taken upon the line 4-4 of Figure 1.

Referring to the drawing in detail, it will be seen that the unit embodying the present invention comprises an elongated casing 1 which is of generally elliptical cross sectional design. The upper end of this casing is enlarged in the direction of the short axis of the ellipse to form a substantially cylindrical head 2, the longitudinal axis of which extends parallel to the long axis of the ellipse of the casing. One end of the head, as for example, the end 3 which may be termed the bow end, has extending from the central portion thereof of the bearing sleeve 4 in the forward end of which the packing nut 5 threadably engages and in the opposite end of the head there is mounted a rear bearing 6 which is in alignment with the bearing sleeve 4.

The bow end of the head 2 is designed to be positioned against the rear face of the stern post of a boat, when the unit is mounted in position, the stern post of a boat being shown conventionally and indicated by the numeral 7 and securing bolts 8 project from this end of the head for engagement in the stern post, while the sleeve bearing 4 extends therethrough.

The forward edge of the casing 1 from the bow end of the head downwardly through substantially half its length, is flattened as indicated at 9 to contact firmly with the rear face of the stern post and at the rear end of this flattened portion lateral bosses 10 are formed on the casing from the faces of which bolts 11 project for extension into the stern post 7. The bosses 10 are intended to en-

gage the stern post of the boat adjacent the lower end thereof, so that substantially the lower half of the casing lies below the end of the stern post in the manner shown.

5 The top of the casing head 2 has an opening formed therethrough, which is normally closed by the cap 12. This opening is provided to permit of the introduction into the casing of lubricating grease with which the 10 casing is kept packed, while the unit is in operation.

At its lower end the casing is slightly enlarged laterally to provide the foot portion 13 which is of substantially circular cross sectional design and which extends across the lower end of the casing substantially parallel with the head 2. The forward and rear or bow and stern ends 14 and 15, respectively, of this foot portion are formed to receive bearings 15^a through which extends a propeller shaft 16, the bow end of the shaft carrying a propeller 17.

Within the casing there extends longitudinally therethrough the vertical shaft 18, suitably mounted at each end in bearings 19^a fitted in receiving recesses in the webs 19^a in and adjacent each end of the casing, carrying at its upper and lower ends the bevelled gears 20 and 21, respectively.

30 The gear 21 meshes with a similarly formed gear 22 mounted upon the propeller shaft 16, while the gear 20 meshes with a gear 23 located in the rear portion of the head 2 and carried upon the engine shaft 24 which extends from the engine crank shaft (not shown) through the bearing sleeve 4 and into the head, in the manner shown.

From the foregoing description it will be readily seen that with the present unit the 40 engine of a boat upon which the unit is mounted may be positioned as close to the stern of the boat as the construction thereof will permit and the full power thereof be as effectively delivered to the propeller 17, as 45 when the motor is mounted in the usual position in the central portion of the boat.

In addition to this, as pointed out in the foregoing paragraphs, many advantages result from the use of this unit, such as the advantages of mounting the engine horizontally instead of upon an inclination as in the usual case, the advantages of removing the engine from the main part of the boat where a great deal of room is ordinarily taken up, 55 which may be converted to the comfort of the occupants, and the advantages in the building of the boat by the elimination of the usual shaft log required when the drive shaft is run along the boat keel.

60 Due to the cross sectional design of the casing, which houses the longitudinally extending shaft 18 slight resistance is offered thereby to its passage through the water. It will also be noted that by positioning the 65 propeller 17 to face the bow of the boat under

the stern post, the unit may be conveniently mounted without interfering with the rudder structure of the boat.

Having described my invention, what I claim is:—

70 1. A boat propeller unit comprising an elongated casing adapted to be mounted in substantially vertical position on the stern of a boat, a plurality of bosses mounted on said casing spaced inwardly from the opposite ends thereof, attaching bolts secured to said bosses for attaching the casing to the stern of a boat, a drive shaft transversely mounted in the upper end of said casing, a vertically arranged shaft mounted in said casing and having gear connection with said drive shaft, a propeller shaft transversely mounted in said casing and having gear connection with said vertical shaft, and anti-friction means for each of said shafts.

75 2. A boat propeller unit comprising an elongated casing having an open upper end adapted to be mounted in substantially vertical position on the stern of a boat, a plurality of bosses spacedly positioned on the forward edge portion of said casing and in spaced relation to each other, a plurality of bolts secured to said bosses for attaching the casing to the stern of a boat, a drive shaft transversely mounted in the upper end of said casing, a vertically arranged shaft mounted in said casing, a closure cap for said opening in said casing, lubricating means mounted in said cap for lubricating the interior of the casing, a propeller shaft transversely mounted in the lower end portion of said casing, and anti-friction bearings for each of said shafts, said casing being provided with a plurality of communicating lubricating openings whereby to lubricate each of said bearings.

80 90 In testimony whereof I hereunto affix my signature.

FRANK HERBST.
